UNITED STATES PATENT OFFICE.

JAMES CAREY DAVIS, OF HINSDALE, ILLINOIS.

RAILWAY TIE.

Application filed October 24, 1923. Serial No. 670,485.

To all whom it may concern:

Be it known that I, JAMES CAREY DAVIS, a citizen of the United States, and a resident of Hinsdale, in the county of Du Page and 5 State of Illinois, have invented a certain new and useful Improvement in Railway Ties, of which the following is a specification.

This invention relates broadly to railway rail supports, and more particularly to improvements in railway ties, more especially 10 to the provision of an improved composite railway tie which is characterized by the features of rigidity of support, durability, simplicity and altogether improved efficiency 15 in use.

The principal objects and advantages which characterize this invention reside in the provision of an improved railway tie; the provision of an improved railway tie of 20 metallic construction; the provision of an improved metallic foundation railway tie; the provision of an improved railway tie including a metallic supporting element and a non-metallic rail support; the provision 25 of improved means for supporting a railway tie including a metallic base, non-metallic rail supports, and means for fixedly retaining said supports in said tie; the provision of an improved composite railway tie 30 which may be manufactured at low cost.

This invention is furthermore especially characterized by the provision of improved means for detachably connecting a metallic railway tie and a non-metallic rail support, 35 so that renewals of the rail supports may be facilely accomplished by one man, for instance, the track walker, and without the necessity of removing the entire tie from the position which it occupies normally; the provision of an improved composite railway tie including a metallic support which gives 40 the desired weight and rigidity, and a non-metallic rail support which permits of insulation of the rails of a railway track and 45 at the same time affords the desired resiliency, thus preventing the transmittal of shocks due to the travel of a train thereover, and thereby increase the life of the tie.

50 The foregoing and such other objects and advantages as may appear or be pointed out as this description proceeds, are attained in the structural embodiments illustrated in the accompanying drawings, in which:

Figure 1 is a side elevational view of a 55 portion of a railway tie constructed in accordance with this invention, showing a rail in position thereon;

Figure 2 is a plan view with the rail and 60 its support removed;

Figure 3 is a view similar to Figure 2, 65 showing the rail and its support in position;

Figure 4 is an end elevational view looking 70 at the left hand end of Figure 1;

Figure 5 is a vertical sectional view taken 75 on the line 5—5 of Figure 1, looking in the direction indicated by the arrows;

Figure 6 is a vertical sectional view of an 80 alternative form of the device shown in Figure 1;

Figures 7 and 8 are elevational views of 85 further alternative forms of the invention;

Figure 9 is a vertical sectional view taken 90 on the line 9—9 of Figure 7; and

Figure 10 is a vertical sectional view taken 95 on the line 10—10 of Figure 8.

Referring now more particularly to the drawings and first to the device illustrated in Figures 1 to 5, both inclusive, I provide 100 a base member, generally designated 5, constructed of metal, preferably soft cast steel, and including a medial channel portion 6 having the bottom wall 7 and side walls 8.

The bottom 7 extends throughout the 105 entire tie, and while only one end of the tie is shown and described, it will be understood that the opposite end of the tie is substantially identical with that shown. The base wall 7, for the purposes of drainage 110 and in order to lighten the tie without sacrificing strength, is provided with openings 9 in the end portions 10 and openings 11 in the medial portion of said bottom wall.

The tie is provided near its opposite ends 115 with a pair of pockets, one only of which is shown here, designated 12. The pocket 12 is formed by the provision of a transverse vertical wall 13 defining the outer end of the pocket and, in the present instance, the side 120 walls or flanges 8 are increased in height as at 8^a and 8^b, the walls 8^a and 8^b being of substantially the same height as the end wall 13.

The walls 8^a and 8^b are provided with 125 complementary lugs 14, 14^a and 15 and 15^a. As shown, these lugs, are arranged complementally opposite on the walls of the

6 pocket 12, the lugs 14^a and 15^a having outer beveled ends 16 and 17, respectively, and the non-metallic rail support, such as a wooden block 18 is introduced into said pocket 12 and is provided with longitudinal grooves 19 and 20 which are adapted to engage the complementary lugs 14 and 14^a and 15 and 15^a. The beveled ends 16 and 17 facilitate introduction of the block which is first deposited in the channel 6 and then slid into the pocket, the lugs, as best shown in Figure 5 being arranged on their respective walls about midway of the height of said walls. The lugs thus form means for supporting 10 the wooden block 18 and also for preventing rising of the block in the pocket when a train passes over the tie.

15 In order to secure the block 18 against endwise displacement, the arrangement and disposition of said block in the said pocket is such that one end of the block abuts the end wall 13 for preventing outward displacement of said block, and the walls 8^a and 8^b are provided with openings 21—21, preferably located below the plane of the lugs 14 and 15 whereby a standard rail spike 22 may be driven into the block through each of said openings. There have been four openings provided and it will be obvious that two or more spikes may be inserted and driven into the block. Where necessary additional openings may be provided, but for ordinary service four spikes will serve to effectually retain the block.

20 35 The bottom wall 7 at the pocket 12 is provided with drain openings 23—23, and the end wall 13 in each case is provided with an elongated opening 24 whereby a crow bar or similar instrument may be inserted for driving the block out of a pocket when replacement is desirable or necessary.

25 40 A railway rail 25 has its base 26 resting upon the upper surface of the block 18, said block preferably extending above the upper margins of the walls 8^a, 8^b and 13 so that the rail will not come in contact with the metallic tie. Screw spikes 27—27 of the conventional type are driven into the block and serve to retain the rail in position thereon, said spikes being of sufficient length 45 preferably to extend below the planes of the lugs 14 and 15 so that in the event that the block, in service, should split, the screw spikes will serve to hold the parts of the block together until replacement may be made. As shown in Figure 3 the screw spikes 27 are preferably staggered, so that the strain will be evenly distributed upon the block.

45 60 Referring now to Figure 6, a construction similar to that of Figure 1 is illustrated, the pocket 12^a being open at the bottom as well as at the top and having an end wall 13^a and side walls 9^a, only one of which latter is 65 shown. The walls 9^a and 13^a are provided

with lugs 28 and 29, respectively, and these lugs seat in recesses formed in the ends and sides of the wooden block 30.

65 In this instance the block is slid into position similarly as the block 18 and the lugs 31 are bent downwardly to retain the block, said lugs being formed integrally with the walls 9^a. In order to afford additional means for preventing displacement of the block, a transverse bolt 32 extends through the walls 9^a and abuts the inner end of the block. It will be obvious that the bolt 32 may pass through the center of the block 30 as will appear in the alternate forms of the invention shown in Figures 7 to 10, inclusive, and it will also appear that the bolt might be employed in the form of the invention illustrated in Figures 1 to 5, inclusive.

70 Referring now to the device shown in Figures 7 and 9 the metallic tie includes the medial channel portion 33 having its side walls increased in height as at 34 and 35 to form, with the end wall 36, a pocket 37 which is adapted to receive the block 38, 75 which is formed preferably of wood.

75 The upper edges of the walls 34 and 35 are bent inwardly to provide horizontal flanges 39—39 which engage the cutaway portions 40—40 of the block 38 and thus prevent upward displacement of said block.

80 Endwise displacement of the block is prevented in one direction by the end wall 36 and in the opposite direction by the transverse bolt 41, one only of said bolts being 100 shown. It will be understood, of course, that there may be a plurality of the bolts provided if desired, and it will also appear that spikes may be employed here similarly as those employed in the device of Figure 1. 105

85 Suitable drainage openings 42 may be provided in the bottom of the tie and this tie may also be lightened in construction in the same way that the tie shown in Figure 1 is lightened.

90 The invention shown in Figures 8 and 10 is similar to that shown in Figure 7 with the exception that the walls 34^a and 35^a are provided with recesses 43 and 44 in their upper margins for accommodation of the 115 rail carried by the block 45.

95 The block 45 is mounted in a pocket having an end wall 36^a connecting the side walls 34^a and 35^a, and the recesses 43 and 44 afford extensions 46—46 and 47—47 bent to 120 form overlying flanges 48 which engage the top of the block 45 and prevent its upward displacement.

100 Similar to the form of the invention shown in Figure 7, endwise displacement of the block outwardly is prevented by the wall 36^a and similarly displacement in the opposite direction is prevented by the transverse bolt 41^a.

105 It will be observed that in the forms of 120

the invention shown in Figures 1 to 6, inclusive, the lugs on the vertical walls of the pocket serve to prevent any shearing stress on either the retaining spikes 22 or on the 5 bolts for a similar purpose, the base of the tie and the flanges shown in the forms of Figures 7 to 10, inclusive, relieving the retaining bolts of any vertical shearing stress.

It will be observed that in all of the forms 10 of the invention herein shown and described replacement of the wooden block may be readily accomplished by one man and that it is unnecessary to remove the tie from the road bed when such replacement is being 15 made. Furthermore the employment of wooden blocks as shown results in a great saving in upkeep of the road bed and also permits of utilizing old railway ties of wood which now must be in most cases discarded.

20 Having thus described my invention and illustrated its use, what I claim as new and desire to secure by Letters Patent is:

1. In a device of the character described, in combination, a continuous metallic supporting member, provided with a pocket open at its top and at one end, a non-metallic block adapted to be slid into said pocket, means in the pocket above the bottom thereof for supporting said block, and removable 30 means arranged transversely of the tie and extending into said block.

2. In a device of the character described, in combination, a continuous metallic supporting member, provided with a pocket open at its top and at one end, a non-metallic block adapted to be slid into said pocket, means in the pocket above the bottom thereof and integral therewith for supporting said block, and removable means arranged transversely of the tie and extending into said block.

3. In a device of the character described, in combination, a continuous metallic supporting member, provided with a pocket open at its top and at one end, a non-metallic block adapted to be slid into said pocket, lugs on the inner surfaces of the walls of said pocket for directly supporting said block, and means extending into said block 50 for retaining same.

4. In a device of the character described, in combination, a continuous metallic supporting member, provided with a pocket open at its top and at one end, a non-metallic block adapted to be slid into said pocket, lugs on the inner surfaces of the walls of said pocket for directly supporting said block and removable means extending into said block for retaining same.

60 5. In a device of the character described, in combination, a metallic supporting member having a pocket, a non-metallic block having one dimension less than the corresponding dimension of said pocket, means 65 entering recesses in the block for preventing

displacement of the block in one direction, and retaining means removable from the tie and abutting one end of said block.

6. In a device of the character described, in combination, a metallic supporting member having a pocket, a non-metallic block having one dimension less than the corresponding dimension of said pocket, means 70 entering recesses in the block for preventing displacement of the block in one direction, and retaining means extending transversely 75 of the tie and engaged with said block.

7. In a device of the character described, in combination, a continuous metallic supporting member having a pocket, a non-metallic block having one dimension less than the corresponding dimension of said pocket, means integral with the pocket for preventing 80 displacement of the block in one direction, and retaining means extending transversely 85 of the tie and entering said block.

8. In a device of the character described, in combination, a continuous metallic supporting member having a pocket, a non-metallic block having one dimension less than the corresponding dimension of said pocket, means integral with the pocket for preventing 90 displacement of the block in one direction, and spikes passing through the tie and 95 engaging said block.

9. In a device of the character described, in combination, a metallic supporting base provided with a pocket open at one end and provided with inwardly directed projections, and a non-metallic block having cutaway 100 portions for reception of said projections when the block is inserted through said open end.

10. In a device of the character described, in combination, a metallic supporting base provided with a pocket open at one end and provided with inwardly directed projections, a non-metallic block having recesses for reception of said projections when the 110 block is inserted into said pocket, and removable means for engagement with the tie and block for retaining said block.

11. In a device of the character described, in combination, a metallic supporting base provided with a pocket open at one end and provided with inwardly directed projections, a non-metallic block having recesses for reception of said projections when the block is inserted into said pocket for retaining the block against vertical displacement, and means for engaging the tie and block for preventing endwise displacement of said block.

12. In a device of the character described, in combination, a metallic supporting base provided with a pocket open at one end and provided with inwardly directed projections, a non-metallic block having recesses for 125 reception of said projections when the block 130

is inserted into said pocket for retaining the block against vertical displacement, and removable means for engaging the tie and block for preventing endwise displacement 5 of said block.

13. In a railway rail support, a metallic base member including a pocket defined by angularly related walls, a rail supporting block mounted in said pocket, a series of 10 lugs on said walls for supporting the block, and removable transversely arranged means for preventing endwise displacement of said block.

14. In a device of the character described, 15 a metallic railway tie having a pocket, a non-metallic rail supporting element in said pocket, removable means for securing said supporting element in position, and means in said pocket for relieving said first mentioned means of shearing stresses.

15. In a device of the character described, 20 a metallic railway tie having a pocket, a rail supporting element in said pocket, removable means for securing said supporting element in position, and means in said pocket for relieving said first mentioned means of shearing stresses.

16. In a device of the character described, 25 a metallic railway tie having a pocket, a rail supporting block in said pocket, removable means for securing said supporting block in position, and means in said pocket for relieving said first mentioned means of shearing stresses.

17. In a device of the character described, 30 a metallic railway tie having a pocket, a non-metallic rail supporting element in said pocket, removable means for securing said supporting element in position, said securing means passing through the tie into said supporting element, and means for preventing upward displacement of said supporting element and for relieving said securing means of lateral stresses.

18. In a device of the character described, 35 in combination, a railway tie having a pocket, a rail supporting member in said pocket, removable means for preventing movement in one direction of said block in the pocket, and means in said pocket for relieving said removable means of lateral stresses in another direction.

19. In a device of the character described, 40 in combination, a railway tie having a pocket, a rail supporting member in said pocket, removable means for preventing

movement in a longitudinal direction of said block in the pocket, and means in said pocket for relieving said removable means of lateral stresses in another direction. 60

20. In a device of the character described, 65 in combination, a railway tie having a pocket, a rail supporting member in said pocket, removable means for preventing movement in a longitudinal direction of said block in the pocket, and means in said pocket for relieving said removable means of lateral stresses in a vertical direction. 70

21. In a device of the character described, 75 in combination, a continuous metallic supporting member provided with a pocket open at one end, a non-metallic block adapted to be slid into said pocket, means in the pocket integral with the walls thereof for supporting said block and removable means arranged transversely of the tie and extending into said block. 80

22. In a railway tie, a continuous metallic supporting member having a pocket open at 85 its top and at one end and having internal lateral projections, and a rail support having recesses for reception of said projections when the rail support is introduced into the pocket through said open end. 90

23. In a railway tie, a continuous metallic 95 supporting member having a pocket open at its top and at one end and having internal lateral projections, a rail support having recesses for reception of said projections when the rail support is introduced into the pocket through said open end, and spikes 100 passing through the walls of said pocket into said rail support.

24. In a railway tie, a continuous metallic 105 supporting member having a pocket open at its top and at one end and having internal lateral projections, and a rail support having recesses for reception of said projections when the rail support is slid into the pocket through said open end. 110

25. In a device of the character described, 115 in combination, a continuous metallic supporting member having a pocket, a non-metallic block having one dimension less than the corresponding dimension of said pocket, means integral with the pocket for preventing displacement of the block in one direction, and spikes passing through the tie and engaging said block. 105

In testimony whereof I have hereunto signed my name.

JAMES CAREY DAVIS.
